US0D1077815S

(12) **United States Design Patent** (10) **Patent No.:** **US D1,077,815 S**
(45) **Date of Patent:** **** Jun. 3, 2025**

(54) **DOCKING STATION**

(71) Applicant: **Ugreen Group Limited**, Shenzhen (CN)

(72) Inventors: **Qingsen Zhang**, Shenzhen (CN); **Junling Chen**, Shenzhen (CN); **Changjian Mo**, Shenzhen (CN)

(73) Assignee: **UGREEN GROUP LIMITED**, Shenzhen (CN)

(**) Term: **15 Years**

(21) Appl. No.: **29/858,731**

(22) Filed: **Nov. 3, 2022**

(51) LOC (15) Cl. **14-02**

(52) U.S. Cl.

USPC **D14/434**

(57) **CLAIM**

The ornamental design for a docking station, as shown and described.

DESCRIPTION

FIG. 1 is a front and top perspective view of a docking station, showing our new design;

FIG. 2 is a rear and bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof; and,

FIG. 8 is a bottom plan view thereof.

The broken lines in the figures illustrate portions of the docking station that form no part of the claimed design.

1 Claim, 8 Drawing Sheets
